HOLDER FOR TRADING STAMPS, BOOKS
AND THE LIKE

Robert J. Goodyear, 509 W. Queen St., Inglewood, Calif.

Filed Mar. 29, 1960, Ser. No. 59,930

Term of patent 14 years

(Cl. D33—2)

Figure 1 is a perspective view of a holder for trading stamps, books, and the like showing my new design;
I claim:

The ornamental design for a holder for trading stamps, books, and the like, substantially as shown.
